UNITED STATES PATENT OFFICE.

FREEBORN F. RAYMOND, 2d, OF NEWTON, MASSACHUSETTS.

METHOD OF FORMING HEEL-RANDS.

SPECIFICATION forming part of Letters Patent No. 357,735, dated February 15, 1887.

Application filed November 1, 1886. Serial No. 217,660. (No model.)

To all whom it may concern:

Be it known that I, FREEBORN F. RAYMOND, 2d, of Newton, in the county of Middlesex and State of Massachusetts, a citizen 5 of the United States, have invented a new and useful Improvement in Rands and Method of Making the Same, of which the following is a full, clear, and exact description, reference being had to the accompanying drawings, forming a part of this specification, in explaining its nature.

The object of the invention is to make a formed rand from flat stock without waste; and it consists in cutting or dinking from the 15 stock a rand-blank of suitable shape and configuration, and then making a cut from the outer edge diagonally across the same very nearly to the inner edge, and then folding this cut section inward to make an inward continuation of the rand, and then flattening the same by pressure.

In the drawings, Figure 1 is a view in perspective of a rand-blank, showing the line upon which the rand is divided. Fig. 2 shows 25 in perspective the complete rand.

A represents the rand-blank. It is cut from flat stock, has the outer edge, a , the inner edge, a' , and is of a shape to fit the heel end of a sole or heel-seat of the heel. It is then submitted to a cutting or skiving operation, 30 whereby a diagonal cut, a^2 , is formed in the blank from the lower outer edge to very nearly the inner edge, a' , the cut extending to a point or line about midway the thickness of the

stock at this point, and near enough to the 35 edge a to permit the lower section, a^3 , thus separated from the remainder of the blank, to be turned inward, and to make in effect an inward continuation of the rand. To facilitate the turning or folding of this section, V-shaped 40 pieces may be removed from it before it is folded. The rand-blank as then prepared is submitted to the operation of compression dies or rolls, whereby the part or section folded inward is made uniform with the remainder of 45 the blank, and the result is a wide-formed rand decreasing in thickness from its outer edge inward, made from flat stock without waste or material waste.

Of course it is desirable that the stock or 50 blank should be in a tempered or wet condition.

Having thus fully described my invention, I claim and desire to secure by Letters Patent of the United States—

The method of making formed rands, consisting in cutting from flat stock a rand-blank having the edges a a' , then forming in the blank a cut extending from its lower edge diagonally across or very nearly across the 60 same, then folding this partially-separated section inward to form a continuation of the blank, and flattening the same under pressure, substantially as described.

FREEBORN F. RAYMOND, 2d.
